sterilizer.

WALLACE R. BURKE, *Primary Examiner*.
BERNARD ANSHER, *Assistant Examiner*.

FIG. 1 is a front isometric view of a sterilizer door handle, showing our new design;

FIG. 2 is a side elevation thereof; and

FIG. 3 is a rear elevation thereof.

The broken lines indicating the sterilizer door in FIG. 1 are shown for illustrative purposes only.

We claim:

The ornamental design for a sterilizer door handle, as shown and described.
